UNITED STATES PATENT OFFICE

FREDERICK W. KEWELL, OF OAKLAND, CALIFORNIA

DESIGN FOR A COVER PAPER OR SIMILAR ARTICLE

Application filed December 12, 1928. Serial No. 29,241. Term of patent 3½ years.

To all whom it may concern:

Be it known that I, FREDERICK W. KEWELL, a citizen of the United States, and a resident of the city of Oakland, county of Alameda, State of California, have invented a new, original, and ornamental Design for a Cover Paper or Similar Article, of which the following is a specification, reference being had to the accompanying drawing, forming part thereof.

The drawing is a side elevation of a cover paper with my design.

I claim:

The ornamental design for a cover paper or similar article substantially as shown.

FREDERICK W. KEWELL.
